UNITED STATES PATENT OFFICE.

GEORG FRIEDRICH LEBIODA, OF PARIS, FRANCE.

APPARATUS FOR HARDENING WOOD.

SPECIFICATION forming part of Letters Patent No. 625,042, dated May 16, 1899.

Application filed December 12, 1898. Serial No. 699,051. (No model.)

To all whom it may concern:

Be it known that I, GEORG FRIEDRICH LEBIODA, a subject of the King of Prussia, Emperor of Germany, residing at the city of Paris, 5 in the Republic of France, have made a new and useful invention in Improvements in Apparatus for Hardening Wood, of which the following is a specification.

This invention relates to an apparatus for 10 hardening wood in which the latter is clamped in an iron frame-casing and exposed to very high pressure. In this manner the wood is reduced in volume about ten per cent. to thirty per cent. and receives great solidity 15 and durability. In this method soft wood can be converted into hard wood and the wood thus hardened utilized as a new article of commerce. For this hardening of the wood special presses are required, which allow of 20 an extremely high pressure with a rapid and easy handling and a simultaneous treatment of a large quantity of wood. Especially is it a question of each separate wood block being covered with a metallic sheathing itself, so 25 that the separate wood blocks do not press mutually one against the other, which would cause a very irregular pressing action and a mutual influence of the wood one on the other. The presses hitherto employed are not applicable 30 for the object intended by the present invention, because, on the one hand, they do not allow for the above points, and, on the other hand, they require after the treatment of each separate charge an inconvenient taking apart and reerection or putting together 35 again.

The present invention provides a press which is particularly suitable for working on the large scale required in practice. The 40 separate parts also do not require to be taken apart and put together again for the purpose of recharging. The separate parts are reliably held together in their actual position and also the device for approaching and separating 45 or moving apart the separate plates so arranged that the wood blocks are in no way obstructed in being inserted and withdrawn. A few movements of the hand suffice to convey the treated wood out of the press 50 and to introduce fresh wood in order that it may be in turn treated.

The object of the invention is shown in the accompanying drawings, in which—

Figure 1 is an elevation in partial section; Fig. 2, a side view corresponding therewith, 55 and Fig. 3 a plan view of half the press.

Four columns *p* are mounted on the press-table *c*, which columns carry hydraulic presses *n* and *o*. On the two plungers *m* of the press *n* a pressure-plate *k* is suspended, by means 60 of which a very strong downward pressure can be exerted. Two side plates *e*, mounted on slide-rollers *f*, are arranged mutually adjustable on the press-table *c*, and the wood blocks *a*, having horizontal plates *b* and vertical plates *d* laid between them, are stacked in the manner shown in Fig. 1. The horizontal plates *b* are provided with grooves for the engagement of the vertical plates *d* in such a way that the wood is compressed in the 70 necessary manner by the hydraulic presses *n* and yet cannot expand laterally. The depth of the grooves is so calculated that the compression can take place to the necessary extent and that any falling over of the vertical plates *d* is excluded when the plates *b* are drawn apart in order to discharge the wood which has been treated. The latter takes 75 place automatically as soon as the press-plate *k* has been raised by means of the small press *o*. For this object the separate plates *b* are provided with pins *r* and connected together by hinged or pivoted arms *s* in the manner of lazy-tongs. The uppermost plate *b* is attached to the press-plate *k*, and the lowermost plate *b* is connected by lazy-tongs to suitable 80 projections of the press-table *c*. In this manner the raising of the press-plate *k* causes a perfectly even and simultaneous separation of the separate plates *b* to the amount always 85 necessary and corresponding to the compression. The extent of the separation may be easily limited either by means of suitable projections on the lazy-tongs *s* or stop-rings mounted on the plungers *m* or small chains 90 inserted between the separate plates *b*.

The side plates *e*, which are adjustable on slide-rollers, serve as lateral resistances during the pressing and are supported by adjustable supports *t*, four of which are arranged 100 on each side of the press and are made dependent on one another in their adjustment to allow of their easier operation.

The supports *t* are provided with screws *u*, so that the separate points of support of each 105 plate *e* may be at any time easily adjusted

once for all. The four supports travel in suitable tracks and are each connected by a cross-bar *v* with one another. Projections *w* extend from the cross-bars *v* downward and 5 serve for receiving screwed spindles *x*, provided with right and left hand threads, and these latter are so mounted in the press-table *c* that when hand-wheels *j* are rotated the supports are approached and removed from 10 one another, respectively. Preferably measures are taken either by screws or chains or hooks, so that the plates *e*, even on the return of the supports, are carried along with them. 15 The handling and mode of working of the press hereinbefore described are extremely simple. On the hydraulic presses *n* being depressed the plates *b* descend in the necessary manner, while the plates *e* afford a thoroughly 20 reliable support by reason of the supports adjusted by the hand-wheel *j*, and each separate wood block is surrounded on all sides by an iron casing. Moreover, the hollow spaces of the plates *b* and *d* afford, simultaneously, an 25 extremely convenient means for heating the intermediate plates by means of steam or electricity.

On raising the press-plate *k* the separate plates *b* are moved evenly apart so far that 30 the wood blocks may be withdrawn and fresh ones inserted without the vertical plates *d* being liable to fall down. By means of the hand-wheel *j* the side plates *e* may easily be loosened so far that no lateral pressure any 35 longer exists, and after the press has been supplied with fresh wood they may be adjusted again in the necessary manner. An adjustment of the screws *u* is only necessary once where the wood is of the same size. The 40 screws provided with right and left hand threads, which merely serve for adjusting the supports, no longer prevent the insertion and withdrawal of the blocks of wood, as they

are arranged entirely beneath the wood-feed level. The devices for separating the plates 45 *b* do not interfere in the least with the charging and discharging of the wood.

Having now particularly described and ascertained the nature of my said invention and in what manner the same is to be performed, 50 I declare that what I claim is—

1. An apparatus for hardening wood, characterized by the arrangement of a number of horizontal plates *b* dependent on one another as to their distances apart, and a number of 55 vertical plates *d* engaging in suitable grooves in the said horizontal plates *b*, between which vertical and horizontal plates forming a solid casing the blocks of wood to be treated are exposed to pressure between a presser-plate *k* 60 operated by hydraulic presses and the press-table *c*, side plates *e* being also provided which are supported by two sets of supports *t* which allow of an exact adjustment of the points of support and may be adjusted against 65 one another simultaneously by means of screwed spindles *x* which are provided with right and left hand threads substantially as hereinbefore described.

2. In combination, the press-table *c*, the 70 side plates *e*, the presser-plate *k*, a series of horizontal plates *b* having grooves, the vertical plates *d* fitting in the said grooves to be held vertically thereby and yet permit vertical movement of the plates *b*, means for pressing the side plates *e*, and lazy-tongs for separating the plates *b*, said tongs acting to separate the plates evenly and uniformly, substantially as described. 75

In witness whereof I have hereunto set my 80 hand in presence of two witnesses.

GEORG FRIEDRICH LEBIODA.
